AMERICAN TELEPHONE AND TELEGRAPH COMPANY, A CORPORATION OF NEW
YORK

SIGNALING ARRANGEMENT FOR TELEPHONE SYSTEMS

Application filed June 18, 1931. Serial No. 545,300.

This invention relates to telephone systems and more particularly to improvements in the signaling arrangements associated with the lines of such systems.

5 The arrangements of the invention are particularly applicable for use in common battery central offices of the type in which the line lamp is lighted in series with the line rather than over a local circuit from 10 the contacts of the line relay. When the line lamp is associated in series with the subscriber's line in installations of this type, instances might arise, when the subscriber's line was a long one, wherein the resistance 15 of the long line would be so great that it might be impossible to obtain sufficient brilliancy of the line lamp to give the operator a positive signal of an incoming call. By 20 associating the auxiliary signaling arrangements of the invention with the line lamp in installations of this type a proper brilliance of the lamp, or in other words an adequate signal, may be assured.

25 The arrangements of the invention utilize a differentially wound relay connected in parallel with the line lamp for completing an auxiliary local operating circuit therefor at the central office. One of the advantages of utilizing a relay of this type connected 30 in the manner described, rather than a single wound relay connected across the line, for completing a local operating circuit for the line lamp is the ease with which it may be associated with the desired line without 35 altering the wiring of the switchboard. Other objects and features of the invention will appear more fully from the detailed description of its operation hereinafter given.

40 The invention may be more fully understood from the following description together with the accompanying drawing in the figure of which is a circuit diagram illustrating the invention.

45 In the drawing is shown a subscriber's telephone line L, terminating at a switchboard at a central office, in the jack J. A portion of an operator's cord 6, terminating in the plug P, adapted to connect with the jack J, is shown. The telephone line L extends to a 50 subscriber's station including ringing appara-

tus 1, an induction coil 2, a receiver 3, a transmitter 4 and a switchhook 5, which are well known in the art. At the central office, the ring side of the line L will be grounded, as shown at 7. The tip side of the line will be 55 extended by conductor 8 through the line signal lamp 9 to battery 10 and ground. When the subscriber removes his receiver from the switchhook 5, a circuit will be closed from ground 7 over the ring side of the line, through the subscriber's set, over the tip side of the line, over conductor 8, filament of lamp 9 to battery 10 and ground. When the subscriber removes his receiver from the switchhook 5, a circuit will be closed from ground 60 7 over the ring side of the line, through the subscriber's set, over the tip side of the line, over conductor 8, filament of lamp 9 to battery 10 and ground. If the line L should 65 be a long one, its resistance might be so great that the lamp 9 would not light with the usual brilliance and a proper signal might not be given to the operator at the central office. Accordingly, the arrangements of the invention 70 provide an auxiliary local circuit for the line lamp 9 at the central office. This circuit will include one of the differentially arranged windings of a relay 12. When the previously traced circuit for the line lamp is closed by removal of the receiver from the switchhook at the subscriber's station, ground will 75 be applied to conductor 11 and through the right hand winding of relay 12 to battery 13 and ground. This will operate the relay 12. The operation of the relay 12 will connect 80 ground over its armature and contact to the left hand winding of the relay. However, the windings of the relay are so designed that the effect of the current through the right hand winding will overcome the effect of current 85 through the left hand winding and the relay will remain held operated. The following local circuit for the line lamp 9 will then be completed; from ground, armature and contact of relay 12, left hand winding of relay 12, conductor 11, filament of lamp 9 to battery 10 and ground. As this circuit is of relatively 90 small resistance, the line lamp will be operated with its customary brilliance to give the proper signal to the operator at the central 95 office. 100

office. When the subscriber restores his receiver to the switchhook and opens the circuit L or when the operator plugs into the jack, ground will be removed from conductor 11. 5 Under these conditions, the right hand winding of relay 12 will be connected to batteries 10 and 13. As the polarities of these batteries are the same, the current through the right hand winding of relay 12 will be reduced 10 so that the effect of the current in the left hand winding will be equal and opposite to the effect of the current in the right hand winding and the relay will be released. This will restore the circuit to its normal condition. 15 While the invention has been disclosed as embodied in certain specific arrangements which are deemed desirable, it is understood that it is capable of embodiment in many and other widely varied forms without deviating from the spirit of the invention, as 20 defined by the appended claims.

What is claimed is:

1. A telephone signaling system comprising a subscriber's telephone line terminating 25 at a central office, a line signal lamp connected in series with said line at said central office, relay means connected in parallel with said lamp, and means controlled by said relay for completing a local auxiliary operating circuit for said lamp at said central office. 95

2. A telephone signaling system comprising a subscriber's telephone line terminating at a central office, a line signal lamp connected in series with said line at said central office, a differentially wound relay having an operating winding connected to said subscriber's line in parallel with said lamp, and means for completing a local auxiliary operating circuit for said lamp through the other winding of said relay. 100

3. A telephone signaling system comprising a subscriber's telephone line terminating at a central office, a line signal lamp connected in series with said line to battery at said central office, an auxiliary circuit connected from battery to said subscriber's line in parallel with said lamp at the central office, and a differentially wound relay having an operating winding included in said auxiliary circuit and means controlled over its armature and contact for connecting its other winding to ground. 110

4. A telephone signaling system comprising a subscriber's telephone line terminating at a central office, a line signal lamp connected in series with said line to battery at said central office, an auxiliary circuit connected from battery to said subscriber's line in parallel with said lamp at the central office, and a differentially wound relay having an operating winding included in said auxiliary circuit and means controlled over its armature and contact for connecting its other winding to ground, said operating winding being 125

designed to normally have greater effectiveness than the other winding of said relay.

5. A telephone signaling system comprising a subscriber's telephone line terminating at a central office, a line signal lamp connected in series with said line to battery at said central office, an auxiliary circuit connected from battery to said subscriber's line in parallel with said lamp at the central office, and a differentially wound relay having an operating winding included in said auxiliary circuit and means controlled over its armature and contact for connecting its other winding to ground, said relay windings being so designed with respect to said circuits that the effectiveness of the operating winding will be greater than the effectiveness of the other winding of said relay when said telephone line is closed and the effectiveness of said windings will be equal when said telephone line is opened. 85

In testimony whereof, we have signed our names to this specification this 17th day of June, 1931.

HENRY M. BASCOM.
STANLEY F. NELSON.
